FLOOR MAT

Meyer Steinberg, Woodmere, N.Y., assignor to Ideal
Rubber Products Co., Brooklyn, N.Y.

Filed Apr. 30, 1964, Ser. No. 79,757

Term of patent 14 years

(Cl. D9—6)

FIG.1

FIG. 1 is a top view of a floor mat embodying my new design.

FIG. 2 is a front view of the floor mat taken on the line 2—2 of FIG. 1.

FIG. 3 is a side view of the floor mat taken on the line 3—3 of FIG. 1.

The drawing is stippled to indicate contrast.

The dominant features of my design reside in the portions shown in full lines.

I claim:

The ornamental design for a floor mat, substantially as shown and described.
